UNITED STATES PATENT OFFICE.

CHARLES A. FISH AND HENRY W. FISCH, OF LOS ANGELES, CALIFORNIA.

REENFORCED COLLAR.

Application filed April 5, 1923. Serial No. 630,003.

To all whom it may concern:

Be it known that we, CHARLES A. FISH and HENRY W. FISCH, citizens of the United States, residing at Los Angeles, in the county of Los Angeles and State of California, have invented new and useful Improvements in Reenforced Collars, of which the following is a specification.

Our present invention relates to the enforcement of launderable collars, and especially ordinary plural-ply launderable collars of linen, or a like textile material.

It is a further object of our invention to utilize linear elements, such as cords or tapes, in strengthening collars, especially in the region of the edges and the folds thereof.

Other objects of our invention will appear from the following description of preferred and alternative embodiments thereof and from the appended claims, taken in connection with the accompanying drawings, in which

Figure 1 illustrates a form of our invention in which we employ a cord extending adjacent the end of a collar and across a fold thereof.

Fig. 2 is an alternative form in which we disclose the use of a thin flat flexible element which may be a tape extending diagonally adjacent the end of a collar and so folded upon itself and secured as to reinforce the same.

In view of the simple character of the invention herein presented, it will be understood that 1 is in each case a collar, and that in that form of our invention which is shown in Fig. 1, the reenforcement of this collar is a mere cord 3 which, although strong, is preferably slender, unless a beading effect is intended to be produced thereby. It will be obvious that, unless the manufacturer intends to produce a conspicuous enlargement at the front edge of the collar, for an artistic effect, the cord employed in reenforcement should be so slender that its presence cannot be detected after the collar has been laundered in the usual way.

In the form of our invention shown in Fig. 2, we have suggested the use of an alternative linear element, which may be a tape 4, which may advantageously be

stitched down on the line 8—8, before the outer elements of a plural-ply collar are secured together; and it should be understood that in those forms of our invention shown in Figs. 1 and 2, the "working" of the button holes need not be so conducted as to cooperate in securing the respective linear reinforcing elements which we have described.

Ordinarily it may be preferable to so design even the external reenforcements which fall within our invention that they shall be comparatively or wholly inconspicuous, and we prefer internal reinforcement.

Although we have shown various alternative forms of our invention, it should be understood that various parts thereof might be independently employed, and that numerous modifications might be made without departing from the spirit and scope of our invention, as the same is indicated above and in the following claims, it being understood that in any case the reenforcement which we employ is so disposed at the ends of the fold of a collar as to prevent tearing or ripping in order to prolong the useful life of any collar to which our invention may be applied.

What we claim is:

1. In a plural-ply fabric collar adapted to be folded longitudinally, a lineal reenforcement disposed between the plies and extending across the fold upon a bias.

2. In a plural-ply fabric collar adapted to be folded longitudinally, a lineal reenforcement disposed between the plies and extending across the fold upon a bias, said reenforcement being adapted to reinforce the fold and the button hole of said collar.

3. In a plural-ply fabric collar adapted to be folded longitudinally, a reenforcement disposed between the plies and inwardly from the end edges of said collar, said reenforcement extending across the fold and having a portion folded upon itself between the plies adapted to reinforce the button hole of the collar.

In testimony whereof we have signed our names to this specification.

CHARLES A. FISH.
HENRY W. FISCH.
